UNITED STATES PATENT OFFICE

CORNELIUS COLLINS, OF LOS ANGELES, CALIFORNIA

BLOCK FOR STEEL STUDDING AND THE LIKE

Application filed June 26, 1928. Serial No. 288,373.

This invention relates to blocks and the latter in combination with metallic bars adapted to serve as skeletons or frames for walls, ceilings and the like. In the building up of walls and ceilings with such frames, nailing blocks for attaching trim, picture molding, casing for doors and windows and fixtures is desirable. Furthermore, some means for nailing the bases to the wall are commonly provided, such as base strips. The present invention appertains to a nailing block which may be attached to the studs of a wall or beams of a ceiling skeleton and serve as a base for nailing various devices thereto.

It is the primary object of this invention to provide a nailing block which is simple in structure, economical, easily attached, stable, and durable. It is another object of this invention to provide the combination of a bar and block requiring no special tools or skill in assembly of the blocks on the bars.

Other objects will be apparent from the subjoined specification in which an embodiment of the invention is disclosed and illustrated in the accompanying drawing, in which:—

Fig. 1 is a front elevation of a nailing block; Fig. 2 is a side elevation thereof; Fig. 3 is an elevation of a fragment of a metallic bar having my improved block secured thereto; and Fig. 4 is a side elevation of the assembly shown in Fig. 3.

Referring with more particularity to the drawing, 5 marks a metallic channel bar, the legs thereof being cut or slit transversely to the length of the bar to provide wings 6. These wings are bent outwardly from the legs and preferably at right angles thereto. The wings are slit in a direction extending lengthwise of the bar to provide bendable fingers 7. The slits flare so that the fingers have a greater breadth at their roots than at their tips. Nailing blocks preferably of wood are provided. These blocks have a flat base 8

and an interrupted outer surface comprising a central portion 9 which is substantially the depth of the plaster coat to be applied to the wall. The end portions of the surface indicated by 10 provide a thickness substantially equal to the depth of the wings 6 between the fingers and the plane of the legs of the bar. Kerfs or slits 11 are provided in the portions of the blocks at the end to receive adjacent wings 6. The blocks are placed in desired position upon the bar with wings 6 extending through the kerfs. The fingers 7 are then turned to overlie the outer face of the block and rest thereon to anchor the latter in position. Due to the tapering inner edges of the fingers, they will serve to wedge the blocks against the bar and securely hold the latter in position.

In the construction of a wall, the blocks are applied to the steel stud at such locations as it is desirable to attach or nail members thereto. These blocks may be placed at the base of the stud and the wall plastered flush with the surface portions 9. This provides means for nailing the faces, or such other elements of the wall in position. Various other uses not described herein will be apparent to those skilled in the art.

What I claim is:—

1. In combination with a metallic bracket shaped bar having a leg with spaced wings extending laterally with respect to the plane of a leg of said bar, each of the adjacent wings being formed with bendable fingers extending lengthwise of said bar, a nailing block disposed against said leg and having openings in which adjacent wings are disposed with the fingers projecting beyond the outer face of said block, said fingers being angularly disposed to overlie said block.
2. In combination with a metallic bracket shaped bar having a leg with spaced wings extending laterally with respect to the plane of said leg, each of adjacent wings being formed with bendable fingers extending

lengthwise of said bar, a nailing block having end extensions of reduced thickness provided with openings in which adjacent wings are disposed with the fingers projecting beyond the outer face of said block, said fingers being angularly disposed to overlie the outer face of said block.

3. In combination with a metallic bracket shaped bar having a leg with spaced wings 10 extending laterally with respect to the plane of said legs, each of said wings being slit lengthwise of said bar to form bendable fingers, a nailing block disposed against said leg and having openings in which adjacent 15 wings are disposed with the fingers projecting beyond the outer face of said block, said fingers being angularly disposed to overlie the outer face of said block.

4. In combination with a metallic bracket 20 shaped bar having a leg with spaced wings extending laterally with respect to the plane of said leg, each of the adjacent wings being slit lengthwise of said bar to form bendable fingers, a nailing block disposed against said leg and being slit at the ends to form openings 25 in which adjacent wings are disposed with the fingers projecting beyond the outer face of said block, said fingers being angularly disposed to overlie the outer face of 30 said block.

5. In combination with a metallic bracket shaped bar having a leg with spaced wings 35 extending laterally with respect to the plane of said leg, each of the adjacent wings being formed with bendable fingers, a nailing block having end extensions of reduced thickness slit to provide openings in which adjacent wings are disposed with the fingers projecting beyond the outer face of said block, said 40 fingers being angularly disposed to overlie the outer face of said block.

6. In combination with a metallic bracket shaped bar having a leg with spaced wings 45 extending laterally with respect to the plane of said leg, each of the adjacent wings being slit lengthwise of said bar to form bendable fingers having a greater breadth at the base than at the tip, a nailing block having an interrupted outer face to provide sections of 50 reduced thickness, said sections being provided with openings in which adjacent wings are disposed with the fingers projecting beyond the outer face of said block, said fingers being angularly disposed to overlie the outer 55 face of said block.

7. In combination with a metallic bracket shaped bar having a leg with spaced wings 60 extending laterally with respect to the plane of said leg, each of the adjacent wings being slit lengthwise of said bar to form bendable fingers having a greater breadth at the base than at the tip, a nailing block slit at the ends to form openings in which adjacent wings are disposed with the fingers projecting beyond the outer base of said block,

said fingers being angularly disposed to overlie the outer face of said block.

8. In combination with a metallic stud 70 comprising a bar of channel form with a leg thereof having integral spaced wings extending from the marginal edges thereof with their planes parallel to the web of said bar, each of the adjacent wings being formed with bendable fingers, a nailing block having end extensions of reduced thickness provided with openings in which adjacent wings are disposed with the fingers projecting beyond the outer face of said block, said fingers being angularly disposed to overlie the outer face of said block.

9. In combination with a metallic stud 75 comprising a bar of channel form with a leg thereof having integral spaced wings extending from the marginal edges thereof with their planes parallel to the web of said bar, each of the adjacent wings being slit lengthwise of said bar to form bendable fingers with the bases thereof of greater breadth than the tips, a nailing block disposed against said leg and having openings in which adjacent wings are disposed with the fingers projecting beyond the outer face of said block, said fingers being angularly disposed to overlie the outer face of said block.

10. In combination with a metallic stud 80 comprising a bar of channel form with a leg thereof having integral spaced wings extending from the marginal edges thereof with their planes parallel to the web of said bar, each of the adjacent wings being slit lengthwise of said bar to form bendable fingers having bases of greater breadth than the tips, a nailing block having an interrupted outer face to provide sections of reduced thickness, 85 said sections being provided with openings in which adjacent wings are disposed with the fingers projecting beyond the outer face of said block, said fingers being angularly disposed to overlie the outer face of said block.

11. In combination with a metallic stud 90 comprising a bar of channel form with a leg thereof having integral spaced wings extending to the marginal edges thereof with their planes parallel to the web of said bar, each 95 of the adjacent wings being slit lengthwise of said bar to form bendable fingers, the bases of said fingers being of greater breadth than the tips, a nailing block slit at the ends to form openings in which adjacent wings 100 are disposed with the fingers projecting beyond the outer face of said block, said fingers being angularly disposed to overlie the outer face of said block.

12. In combination with a metallic stud 110 comprising a bar of channel form with a leg thereof having integral spaced wings extending from the marginal edges thereof with their planes parallel to the web of said bar, each 115 of the adjacent wings being slit lengthwise of 120 said bar to form bendable fingers, the bases of said fingers being of greater breadth than the tips, a nailing block slit at the ends to form openings in which adjacent wings are disposed with the fingers projecting beyond the outer face of said block, said fingers being angularly disposed to overlie the outer face of said block.

said bar to form bendable fingers with bases of greater breadth than the tips, a nailing block having end extensions of reduced thickness slit to provide openings in which adjacent wings are disposed with their fingers projecting beyond the outer face of said block, said fingers being angularly disposed to overlie the outer face of said block.

In witness that I claim the foregoing I
10 have hereunto subscribed my name this 1st
day of June, 1928.

CORNELIUS COLLINS.
